UNITED STATES PATENT OFFICE

2,013,509

BEER TAP CONE

Fridolin Schiesser, Rheineck, Switzerland

Application October 12, 1934, Serial No. 748,091
In Switzerland October 11, 1933

2 Claims. (Cl. 225—5)

The object of the present invention is a tap cone, especially for taps on barrels, in which the head piece of the outflow-pipe has a recess for receiving air-sterilizing agents, whereby said recess is connected to the bore by way of an air-channel carried parallel to the axis of the outflow-bore of the outflow-pipe, and where furthermore said air-channel is connected with the topmost part of said outflow-bore by way of a cross-bore.

The accompanying drawing shows the object of the invention in an example, with

Fig. 1 showing the tap cone within a tap body, in a cross-section;

Fig. 2 showing a plan of the tap cone and body;

Fig. 3 showing the outflow-pipe alone in plan;

Fig. 4 showing a side elevation of the outflow-pipe; and

Fig. 5 showing a section along line "A—B" of Fig. 1. The tap cone shown possesses an outflow-pipe *a* and a lever *f* serving as grip. Said outflow-pipe *a*, open on one side, shows in its head piece a recess *b* for receiving air-sterilizing agents (such as salicylic cotton) *c*, said recess being connected to an air-channel *d* carried parallel to the axis of said outflow-pipe *a* and leading into the outflow-bore *a*¹; a cross-bore *e* empties into said air-channel *d* and connects the topmost part of the outflow-bore *a*¹ with air-channel *d*, said cross-bore being slightly inclined to the horizontal plane and its purpose is to obtain a complete emptying of outflow-bore *a*¹ after closing the tap.

The head of the outflow-pipe carries a removable lever *f*, disengageable from its turning movement about the outflow-pipe. Said lever shows a bore *g* allowing the entrance of air into said recess *b* of said head piece of the outflow-pipe from above. Lever *f* is secured against being lifted off said head piece by means of a screw *h*. In order to facilitate the insertion of screw

h, when recess *b* is filled with air-sterilizing agents *c*, a casing *i* is provided which keeps the screw-hole open.

The tap cone as a whole is inserted into a tap body *k* in a manner well known, with the latter's vertical bore being fitted with a packing means *l*. In the tap cone shown the particles of air sucked from above through the air-channel by the outflowing liquid are being sterilized. Furthermore is the inside of the outflow-bore being constantly sterilized on the one hand, and on the other hand we obtain, by means of air-channel *d* and cross-bore *e* emptying into it, a complete emptying of the outflow-bore, thus eliminating in a marked degree the possibility of residuals accumulating inside the outflow-bore.

The tap cone being used in combination with a key-tap, the recess of the head piece of the outflow-pipe, which is open from above, could be closed by means of a cover plate provided with a bore.

I claim:

1. A tap cone which has a recess in the head piece of the outflow-pipe for receiving air-sterilizing agents, this recess being connected with the outflow-bore by means of an air-channel parallel to the axis of said bore, said air channel and the topmost part of said bore being connected by means of a cross-bore.

2. A tap cone with a recess in the head piece of the outflow-pipe as an air-sterilizing chamber, said recess being connected with the outflow-bore by means of an air-channel parallel to the axis of said bore, said air-channel and the topmost part of said bore being interconnected by means of a cross-bore, and said head piece carrying a lever disengageable from its turning movement around said outflow-pipe, with said lever having a bore allowing air to enter said recess from above.

FRIDOLIN SCHIESSEER.
